UNITED STATES PATENT OFFICE.

DANIEL I. COBB, OF YPSILANTI, MICHIGAN.

GATE.

SPECIFICATION forming part of Letters Patent No. 329,276, dated October 27, 1885.

Application filed July 9, 1885. Serial No. 171,069. (No model.)

To all whom it may concern:

Be it known that I, DANIEL I. COBB, of Ypsilanti, in the county of Washtenaw and State of Michigan, have invented new and 5 useful Improvements in Gates; and I do hereby declare that the following is a full, clear, and exact description thereof, reference being had to the accompanying drawings, which form a part of this specification.

10 This invention relates to certain new and useful improvements in the construction of swinging farm-gates; and the invention consists in the peculiar construction of the gate-hangings, in the peculiar construction of devices for operating the gate, and in the construction, arrangement, and combination of the various parts, all as more fully hereinafter set forth and claimed.

Figure 1 is a perspective view of my 20 proved gate. Fig. 2 is a plan view of the same.

In the accompanying drawings, which form a part of this specification, A represents the gate, which is provided with the diagonal brace-rod B, the upper end of which projects beyond the heel of the gate at the upper corner, and terminates in an eye, C, designed to engage with the hook or eye D of the brace-rod E, which passes through or over the top 30 of the post F, and is secured to the stake G. The lower corner of the heel of the gate is hung by means of the ordinary hook-and-eye hinge, H. By this manner of hanging the gate all strain is removed from the post, the latter 35 merely serving as a standard over which the continuous brace formed by the rods B and E passes. At a convenient point near the gate-post is placed a standard or post, I, upon the top of which is secured a stelliform turn-table, J, from one arm of which rises a wrist-pin, K, which engages with a slot, a, in the extension-bar L, secured to the gate, as shown. At right angles to the line of fencing or gate, and in line with the post I, are the posts M 40 M', upon which are pivotally secured the levers N N', from which suitable ropes or cables,

O O', pass and are secured to the turn-table, as shown.

In practice, in approaching the gate the driver pushes upon the end of the lever N, 50 which turns upon its fulcrum, and by means of the connections named causes the gate to swing open. Having passed through the gate, the latter is closed by pushing upon the lever N'. 55

It will be observed that when the gate is closed the wrist-pin K of the turn-table is at or about the longitudinal center of the slot in which it operates, and in a direct line with the pivotal point of the turn-table at right angles to the gate, so that when the gate is closed it is self-locked in such position that it cannot be opened without first turning the turn-table. 60

I am aware of the Patents Nos. 65,619 and 65 203,396, and make no claim to the constructions shown therein as forming part of my invention.

What I claim as my invention is—

1. The combination, with a swinging-gate 70 having the slotted bar L projecting rearwardly therefrom, of the turn-table J, having a wrist-pin engaging with said bar, and so arranged that when the gate is closed the line connecting said wrist-pin to the pivoted point 75 of the turn-table is at right angles to the line of the gate.

2. The combination, with a farm-gate, of the hinge-braces B E, the hinge-post F, and the stake G, the slotted bar L, projecting rearwardly from the gate, the turn-table J, engaging the slotted bar by its wrist-pin, the post I, supporting said turn-table, the posts M M', the horizontal levers N N', pivoted thereon, and the cables O O', connecting levers N N' 80 with the turn-table, all constructed, arranged, and operating substantially as set forth. 85

DANIEL I. COBB.
